UNITED STATES PATENT OFFICE.

ERNST FINKING, OF LEIPZIG, GERMANY.

SOUND CONDUIT FOR SOUND-RECORDING AND SOUND-REPRODUCING INSTRUMENTS.

Application filed August 17, 1926, Serial No. 129,848, and in Germany April 8, 1925.

My invention relates to improvements in sound conduits for sound recording and sound reproducing instruments.

With sound reproducing instruments considerable distortion is liable to occur in the reproduction of certain sounds, more particularly musical notes. The notes of a violin, when reproduced, approximate to those of a flute, and so on, the worst example being, 10 probably, that of the bugle and trumpet. Even with the human voice the characteristic personal inflection is largely lost. This distortion or blurring is largely due to the metal walls of the sound tubes which vibrate 15 and produce notes of their own thus creating secondary noises and in part overlaying the music or speech. Another cause of the defect is the rigidity of the joints in the sound-box connections, causing the scratching of 20 the needle, vibrations of the room, and vibrations of the motor to be transmitted.

According to my invention the metal sound conduit leading from the sound box is interrupted in several places by connectors of 25 elastic material, for example rubber, and these connectors may be used at the parts where the tube and horn or flare are supported by the cabinet, panel or frame, so that they constitute elastic bearings.

30 An example of apparatus according to my invention is shown in the annexed drawing, partly in section.

In this example the sound conduit comprises a tone arm a_1 , a tube a_2 and a horn or flare e . The sound box f is joined to the tone-arm in known manner by a rubber connector b , and the tone arm is connected to the tube a_2 by a ball joint g and rubber connector b . Another rubber connector b_2 is 35 provided between the tube a_2 and the horn e . The connectors are so disposed that there is no contact between the metal parts which they respectively connect. The ball of the joint g may also be covered with rubber, so that at this joint also there is no metallic 40 contact with the tone arm. In order to in-

sure that no metal part of the conduit is in contact with the casing h of the instrument, the connectors b_1 and b_2 are placed at the parts where the conduit is supported by the 50 casing. For the same reason the free end of the flare e is held in place by two rubber rings i , which are fastened at the upper wall of the casing around the sound-hole.

Instead of rubber any other elastic material adapted to absorb vibration may be used.

The elastic connectors are highly effective in preventing transmission of secondary noises due to scratching and so on, and the gaps in the metal conduit wholly or largely prevent resonant vibration of the conduit due to the sounds which it transmits. Consequently the recorded sound is reproduced with great purity and accuracy, the characteristic notes and inflexions of the various 60 instruments and voices being retained.

The invention is applicable also to sound recording instruments, and in regard to reproduction it can be applied to all sound reproducing instruments having metal sound 70 conduits.

What I claim is:

1. A phonograph comprising a sound box, a tone arm, a horn, a tube between the horn and the tone arm, resilient means connecting the sound box with one end of the tone arm, resilient means connecting the other end of the tone arm with one end of the tube, and resilient means connecting the other end of the tube with the horn.

2. A phonograph comprising a cabinet, a sound box, a tone arm, a horn, a U-shaped tube between the horn and the tone arm, resilient means connecting the sound box with one end of the tone arm, resilient means connecting the other end of the tone arm with one end of the U-shaped tube, resilient means connecting the other end of the tube with the horn, and resilient means connecting the mouth of the horn with the cabinet.

In testimony whereof I affix my signature.
ERNST FINKING.
